PACKAGE SEALING DEVICE

Cecil Miller and Paul L. Snyder, Pomona, and
Ralph H. Swaisgood, Los Angeles, Calif., as-
signors to Consumer-Pak Machine Co., Pomona,
Calif., a corporation of California

Application January 7, 1949, Serial No. 69,656

19 Claims. (Cl. 216—22)

1

The present invention relates generally to apparatus for sealing bags and other packages of produce such as fruit and vegetables, and more particularly relates to such apparatus which is adapted to be incorporated into a conveyor system of the type conventionally used to convey packages of the type stated.

It is often the practice in packaging oranges, lemons, potatoes, onions, and other types of produce, to place the material directly in bags or other containers of relatively small size in order to deliver the same directly to the consumer. It is desirable in such cases to fasten the bag or other package with a type of fastening means which may be readily removed by the consumer, but which will securely hold the package closed during shipment and handling.

Our invention is particularly adapted for fastening the latter class of package, although it has many other uses. The invention will, therefore, be described herein connection with the packaging of oranges for direct delivery to the consumer, although it will be realized by those skilled in the art that the apparatus described is readily adaptable for use in other packaging fields.

One conventional practice in packaging oranges in the manner just described is to fill mesh bags of the drawstring type, either by weighing out individual parcels of fruit and thereafter dumping the same into the bags, or hanging the bags on a weighing scale and dumping fruit thereinto until a predetermined weight is reached. A scale adapted for the latter purpose is described in the co-pending application of Paul L. Snyder and Cecil Miller, Serial No. 22,186, filed April 20, 1948, and entitled "Apparatus for Weighing and Bagging Materials."

After the bags have been filled as above described, they are usually placed on a conveyor whereby they are carried away from the weighing station. Such a conveyor may comprise, for example, a series of hooks carried by an endless chain, which hooks are positioned and adapted to receive the filled bags hanging from their drawstrings. The weight of the filled bags serves to draw the drawstrings taut and close the mouth of the bag. It is convenient to place whatever sealing or closure-applying apparatus is used, in the path of the conveyor so that as the bags are carried along thereby, they pass through the closure-applying apparatus, thus to fasten the drawstrings and prevent them from loosening to open the mouth of the bag after the same is removed from the conveyor.

2

Thus, it is a major object of our invention to provide apparatus for fastening the drawstrings of a filled bag, whereby to prevent the same from loosening to open the bag during handling thereof.

Another object of our invention is to provide fastening means of the class described which are readily removed when it is desired to open the bag.

Still another object of our invention is to provide fastening apparatus of the class described which is adapted to be interposed in a conveyor system whereby filled bags carried by such system are passed through the apparatus to fasten the drawstrings thereof.

A still further object of our invention is to provide apparatus of the class described which is adapted to be actuated by the individual hooks of a hook-type conveyor system, whereby to apply fastening means to each bag as the same is carried through the apparatus.

Yet another object of our invention is to provide fastening apparatus of the type described in the preceding paragraph which is actuated to deliver fastening means only if a bag is present on the conveyor hook then passing through the fastening station, whereby to avoid wastage of the fastening elements.

The foregoing and additional objects and advantages will be apparent from a consideration of the following detailed description thereof, consideration being given likewise to the attached drawings in which:

Figure 1 is a front elevational view of bag fastening apparatus embodying our invention, such apparatus being incorporated in a bag conveyor system;

Figure 2 is a fragmentary side elevational view of the apparatus illustrated in Figure 1, showing in addition, two bags of produce, one before and one after the operation of the fastening apparatus;

Figure 3 is a plan view, partially sectioned, taken on the line 3—3 in Figure 1;

Figure 4 is an enlarged elevational section taken on the line 4—4 in Figure 3;

Figure 5 is a horizontal fragmentary view taken on the line 5—5 in Figure 1, showing the phase relationship of certain movable parts therein; and

Figure 6 is an enlarged fragmentary plan view, similar to Figure 3 but with certain parts removed to illustrate the operation of underlying parts.

In the drawings, the reference character 10

indicates generally the fastening apparatus which is incorporated in a conveyor indicated generally by the reference character 11. The fastening apparatus 10 is secured to the conveyor by a mounting structure which includes a pair of vertical stanchions 12, interconnected by an adjustable bridge member 13 which consists of an upturned channel welded to a pair of sleeves 14 slidably mounted on the stanchions 12 and adapted to be secured thereto by a pair of set screws 15. The upper ends of the stanchions 12 are secured together by a tie bar 16 welded thereto, a vertical adjusting screw 17 is threaded into the tie bar 16 adjacent the center thereof, and the lower end of the adjusting screw is in turn journally secured to the bridge member 13 whereby rotation of the screw 17 raises or lowers the bridge member 13 to various adjusted positions thereof, wherein it may be clamped by the screws 15 as aforesaid. A handle 18 is secured to the upper end of the screws 17 for the purpose of making such adjustment.

The conveyor 11 is secured to the bridge member 13 by clamping bolts 19, as best seen in Figure 2, and includes a downturned channel-shaped housing 20 in which are carried a pair of transverse axles 22 (one not shown), which in turn carry conveyor chain sprockets 21 for rotation thereon. Power means for driving one of the sprockets is provided, as is conventional in such conveyor system, but, forming no part of the present invention, the drive means is not shown in the drawings. A conventional block chain 23 is carried on the sprocket 21 and at distributed points along the chain outwardly projecting hooks 25 are secured to the chain links, whereby the hooks 25 on the lower span of the chain 23 depend below the edges of the housing 20 and move along the conveyor in the direction of the arrows shown in Figure 2.

Each of the hooks 25 is adapted to carry a filled bag 9 dependent therefrom by the drawstrings 8. It is readily apparent from an examination of Figure 2 that the weight of the material in the bags 9 tends to draw the drawstrings 8 taut, closing the mouth of the bag. It will also be seen that, as the bags reach the end of the conveyor 11 (which may be some distance from the fastening apparatus as indicated by the break in Figure 2), the hooks 25 pass upwardly into the housing 11, thus disengaging and dropping the filled and fastened bag therefrom.

The mechanism by which fastening means are secured to the drawstrings 8 as they pass through the fastening apparatus 10 is principally carried on a pair of lower base plates 30 and 31 (right and left hand respectively), which are mounted on the lower ends of the stanchions 12 by means of collars 32 welded to the plates 30 and secured to the stanchions by set screws 33. Also secured to the right hand base plate 30 is an upstanding bearing tube 34 which rotatably carries therein, a shaft 35, the upper end of which is journaled in the bridge member 13. A feed wheel 38, the purpose of which will be described in more detail hereinafter, is secured to the lower end of the shaft 35 below the right hand base plate 30 through which the shaft 35 projects. Midway along the shaft 35 is carried an escapement wheel or star wheel 36 having a conventional hub secured to the shaft 35 by a set screw 37. The angular relationship between the star wheel 36 and the feed wheel 38 is illustrated in Figure 5.

Secured to the base plates 30 and 31 and projecting parallel to the conveyor are a pair of

spaced guide plates 39 defining between a guide slot 40 which slot continues through the fastening apparatus between the base plates 30 and 31. An additional auxiliary guide plate 41 is mounted to the left hand base plate 31 above the upper surface thereof, whereby to additionally guide the drawstrings as they pass through the fastening apparatus, as will hereinafter be described in more detail.

The fastening means applied to the drawstrings 8 as they pass through the fastening apparatus 10 consist of a pair of adhesive tapes applied face-to-face on either side of the drawstrings, whereby the tapes adhere securely to each other, securing the drawstrings therebetween. The nature and advantages of such fastening means are described in detail in the co-pending application of Cecil Miller and Rudolf Mangold, Serial No. 22,185, filed April 20, 1948, and entitled "Bag Sealer," now Patent 2,536,455 issued January 2, 1951.

Adhesive tape from which short lengths are cut to form the fastening means just described is supplied from a pair of rolls 42 mounted on vertical axles 49 to the base plates 30 and 31, respectively. Lengths 43 of the adhesive tape from the supply rolls 42 are passed forwardly over lateral guide rollers 44 to an apex position 62 in the line of the guide slot 40, where the tape portions 43 contact and adhere to each other. Mutually adhering contact of the tapes is assured by a pressure spring 47 mounted to the base plate 31 which spring yieldingly urges the two contacting tapes against a back-up block 45 mounted to the oposite base plate 30.

Mounted to the left hand base plate 31 at a position just beyond the tape apex 62 is a solenoid operating cutting and sealing device indicated generally by the reference character 50. The actuating mechanism of the cutting and sealing device 50 is enclosed by a housing 51 within which is mounted a solenoid including a coil 52, a plunger 53, and an actuating lever 54. Power to actuate the solenoid coil 52 is supplied through leads 57. The actuating lever 54 is pivoted at the upper end as indicated in Figure 4, and the lower end thereof is engaged by a pin and notch connection with a thrust rod 55 disposed transversely to the slot 40. When the solenoid coil 52 is energized, drawing the plunger 53 thereinto, the operation of the actuating lever 54 is such as to thrust the thrust rod 55 to the right in Figure 4. A return spring 56 is secured to the end of the thrust rod 55 and anchored to the base plate 31 whereby to normally retain the thrust rod 55 in its retracted or left hand position.

As best seen in Figure 6, a chuck member 58 is secured to the right hand end of the thrust rod 55 and carries therein a resilient block 59 and a cutting blade 60 secured into the chuck by a set screw 61. The resilient block 59 may be of sponge rubber or similar material and is positioned and adapted to abut a similar resilient block 46 mounted in a recess in the back-up block 45 on the opposite side of the guide slot 40.

The knife blade 60 is double-edged, and reversible, so that it may be reversed when one edge becomes worn. A recess 48 is formed in the back-up block 45 so that the forward or cutting edge of the blade 60 enters the notch 48 in shearing engagement therewith.

Thus it will be seen that when the solenoid coil 52 is actuated, the thrust rod 55 is thrust across the guide slot 40 whereby the knife blade 60

shears any tape lying in the guide slot, and the two resilient blocks 59 and 46 clamp the tape therebetween, whereby to securely seal them together around the drawstring 8 therebetween.

The solenoid of the cutting and sealing device 50 is connected through leads 51 to an actuating switch 65 mounted on the right hand sleeve 14 and positioned and adapted to be intermittently operated by rotation of the star wheel 36. The actuating switch 65 is adjustably mounted by means of a collar 68, surrounding the sleeve 14, and slidably vertically thereon. The collar 68 may be clamped in any adjusted position by means of a set screw 69.

A number of cam lobes 67 are formed in the upper surface of the star wheel 36, and positioned to engage a roller 66 depending from the actuating switch 65, whereby each time one of the cam lobes 67 passes under the roller 66, the switch 65 is actuated. One such cam lobe 67 is formed on each of the teeth of the star wheel as is shown in Figure 3.

As previously stated, the star wheel 36 and the feed wheel 38 are interconnected by the shaft 35 for concurrent rotation. The angular relationship of these two wheels is illustrated in Figure 5, wherein it will be seen that, at a time when the star wheel is in a position to actuate the switch 65, one of the V-shaped peripheral notches in the feed wheel is in a predetermined position across the slot 40, such as to hold the drawstrings 8 between the resilient blocks 46 and 59. When the hooks 25 move along the conveyor 11, the drawstrings enter the slot 40 and are guided into a notch in the feed wheel 38 whereupon rotation of the latter member carries the drawstrings 8 in guided and controlled motion along the slot 40, and positions the drawstrings 8 exactly between the resilient blocks 59 and 46 at the time the solenoid coil is actuated by operating of the switch 65. Such motion of the feed wheel is assured by the fact that as each of the hooks 25 passes the star wheel 36, the shank of the hook engages one of the teeth of the star wheel, rotating the same through approximately 120°, during which rotating the switch 65 is actuated once. The aforesaid 120° rotation of the star wheel leaves the next succeeding tooth thereof in position to be engaged by the next hook, as can be seen from an examination of Figure 3 wherein the starting position of the star wheel 36 is shown in full lines and an intermediate position at which the switch is actuated is shown in phantom lines.

Having described the construction of the apparatus embodying our invention, the complete operation thereof will now be explained. The filled bags are placed on the conveyor as they are received from the weighing and filling apparatus (not shown). Thereupon the filled bags are carried along the conveyor (to the right in Figure 2) and upon reaching the fastening apparatus 10, the drawstrings 8 of the bag enter the guide slot 40. As the hook 25 approaches a position immediately above the cutting and sealing mechanism 50, the shank of the hook engages the counterclockwise side of one of the teeth in the star wheel 36. Such engagement of the star wheel causes the same to rotate in a clockwise direction, effecting concurrent rotation of the feed wheel 38. It will be noted from an examination of Figures 3 and 5 that when the star wheel 36 is in the "ready" position at which it is engaged by the hook 25, the feed wheel 38 is in such position that one of the peripheral notches therein is

aligned with the guide slot 40 whereby the drawstrings 8 carried along by the hook 25 enter the aforesaid notch.

Thereupon, it will be seen that rotation of the feed wheel 38 carries the drawstrings along the slot 40 and at the same time, inwardly to the inner end of the notch. During the last mentioned movement, the drawstrings 8 encounter the adhesive tape lengths 43 at the apex 62 thereof. Since the tape is wound on the rolls 42 with the adhesive side in, the drawstrings 8 adhere to the tape and unwind a small portion from the rolls 42 as the drawstrings move along the slot 40. Such movement also results in the drawstrings becoming "sandwiched" between end portions 70 of the tapes, due to the action of the spring 47 which presses the tapes together behind the drawstrings.

As previously described, the synchronization of the star wheel 36 and feed wheel 38 is such that the cam lobe 57 passes under the actuating roller of the switch 65 at exactly the instant when the drawstrings 8 are between the clamping blocks 46 and 59. Thus, actuation of the switch 65 causes the sealing and cutting mechanism 50 to move the knife blade 60 across the path of the tape, severing end portions 70 therefrom, and sealing said end portions around the drawstrings 8.

After the sealing and cutting operation just described, the continued movement of the conveyor hooks 25 carry the bag 9 on through the fastening apparatus to the end of the conveyor 11 where the upward movement of the hook 25 disengages the bag 9 and drops the same as shown at the right hand end of Figure 2. The bags are held securely closed by the terminal tape portions 70 sealed around the drawstrings 8.

While the apparatus shown and described herein is fully capable of achieving the objects and providing the advantages hereinbefore stated, it will be realized by those skilled in the art that modifications are possible without departing from the spirit of the invention. For this reason, we do not mean to be limited to the form shown and described, but rather to the scope of the appended claims.

We claim:

1. In apparatus for securing drawstring bags: a conveyor adapted to move said bags along a predetermined path, said conveyor including means to hold the drawstrings of said bag taut whereby to close the opening thereof; a supply of fastening material supported adjacent a predetermined point in said path and disposed to engage said drawstrings adjacent the mouths of said bags; and sealing means responsive to movement of said bags to press a portion of said material into securing engagement with said drawstrings when the latter are at said point in said conveyor movement.
2. In apparatus for securing drawstring bags: a conveyor adapted to move said bags along a predetermined path, said conveyor including means to hold the drawstrings of said bag taut whereby to close the opening thereof; a supply of adhesive tape supported adjacent said path and having a portion thereof extending into said path whereby to securely engage said drawstrings adjacent the mouths of bags moving in said path; and severing means responsive to movement of said bags and adapted to sever said drawstring-engaged portions from said tape supply.
3. In apparatus for securing drawstring bags:

a conveyor adapted to move said bags along a predetermined path, said conveyor including means to hold the drawstrings of said bag taut whereby to close the opening thereof; a supply of adhesive tape supported adjacent a predetermined point in said path; and a sealing mechanism including an element actuated by said conveyor each time one of said bags passes said point, pressure means operatively connected to said element to apply pressure to said tape to secure the same around said drawstrings adjacent the mouth of a bag at said point, and severing means operatively connected to said pressure means to sever said secured portion from said supply.

4. In package sealing apparatus of the class described: a conveyor adapted to move packages along a predetermined path; a pair of rolls of adhesive tape, one supported on either side of said path, said rolls having lengths thereof extending therefrom and adhesively joined at a point in said path with the adhesive surfaces of said lengths facing toward the path of said packages whereby said packages moving in said path encounter said adhesive surfaces at said juncture point; and sealing means responsive to movement of said packages to press portions of said tape lengths into securing engagement with said package when the latter is at said juncture point in said path.

5. In apparatus for securing drawstring bags: a conveyor adapted to move said bags along a predetermined path, said conveyor including means to hold the drawstrings of said bag taut whereby to close the opening thereof; a pair of rolls of adhesive tape, one supported on either side of said path, said rolls having lengths thereof extending therefrom and adhesively joined at a point in said path with the adhesive surfaces facing against said conveyor movement whereby said drawstrings of bags moving in said path encounter said adhesive surfaces at said juncture point; and sealing means responsive to movement of said conveyor to press portions of said tape into mutually adhering engagement around said drawstrings of a bag when the latter is at said point in said path.

6. In apparatus for securing drawstring bags: a conveyor having a plurality of movable hooks each adapted to support one of said bags by the drawstrings thereof; a pair of base plates supported below said conveyor and laterally spaced to define a longitudinal guide slot for drawstrings of bags moved by said conveyor; a pair of rolls of adhesive tape, one supported on each of said guide plates, said tape rolls having lengths extended therefrom and said lengths being adhesively joined at an apex positioned in said guide slot, said tape lengths being disposed with the adhesive surfaces thereof facing against said conveyor motion whereby said drawstrings moved by said conveyor encounter said adhesive surfaces at said apex; feed means including a notched feed wheel positioned and adapted to receive said drawstrings in one of said notches thereof and to rotate to move said drawstrings along said guide slot, and means including an escapement wheel operatively connected to drive said feed wheel and positioned and adapted to be actuated by said hooks moving along said conveyor; and sealing means including a solenoid driven pressure block mounted on one of said base plates, an abutting back-up block mounted on the other of said base plates, and an actuating switch operatively connected to said solenoid driven block and 75

8 positioned and adapted to be periodically operated by said escapement wheel whereby to actuate said solenoid driven block to drive the latter against said back-up block to press said tapes together around said drawstrings.

7. The construction of claim 6 further characterized by having a knife blade secured to said solenoid driven block, said knife blade being positioned and adapted to sever said tape lengths at a point in a mutually adhering length thereof whereby to leave mutually adhering portions clamped around said drawstrings and mutually adhering ends at said apex.

8. In package sealing apparatus of the class described: a conveyor adapted to move packages along a predetermined path; a pair of rolls of adhesive tape, one supported on either side of said path, said rolls having lengths thereof extending therefrom and adhesively joined at a point in said path with the adhesive surfaces of said lengths facing toward the path of said packages whereby said packages moving into said path encounter said adhesive surfaces at said juncture point; sealing means responsive to movement of said packages to press portions of said tape lengths into securing engagement with said package when the latter has just passed said juncture point in said path; and a movable cutter responsive to movement of said packages to sever said portions secured to said package from said rolls, said cutter being disposed adjacent a point in said path beyond said juncture point whereby to leave said extending lengths adhesively joined after said secured portion is severed therefrom.

9. In package sealing apparatus of the class described: a conveyor adapted to move packages along a predetermined path; a pair of rolls of adhesive tape, one supported on either side of said path, said rolls having lengths thereof extending therefrom with outer ends of said lengths in adhesive contact at a juncture point in said path with the adhesive surfaces of said lengths facing toward the path of said packages whereby said packages moving in said path encounter said adhesive surfaces at said juncture point; opposed pressure members engaged with the backs of said tape lengths at said juncture point to hold the same in said adhesive contact, one of said pressure members being yieldable to permit said package to pass between said pressure members, and resilient to rejoin said tape in adhesive contact behind said package as the same moves in said path; and sealing means responsive to movement of said packages to press portions of said tape lengths into securing engagement with said package when the latter is just beyond said pressure members in said path.

10. In package sealing apparatus of the class described: a conveyor adapted to move packages along a predetermined path; a pair of supply rolls of adhesive tape, one supported on either side of said path, said rolls having lengths thereof extending therefrom with outer ends of said lengths in adhesive contact at a juncture point in said path with the adhesive surfaces of said lengths facing toward the path of said packages whereby said packages moving in said path encounter said adhesive surfaces at said juncture point; opposed pressure members engaged with the backs of said tape lengths at said juncture point to hold the same in said adhesive contact, one of said pressure members being yieldable to permit said package to pass between said pressure members, and resilient to rejoin said tape in adhesive con-

tact behind said package as the same moves in said path; sealing means responsive to movement of said packages to press portions of said tape lengths into securing engagement with said package when the latter is just beyond said pressure members in said path; and a cutter connected to said sealing means for concurrent movement therewith, said cutter being disposed to sever said tape at a point between said package and pressure members whereby to leave portions of said tape in adhesive contact behind said package, and ends of said tape supply lengths in adhesive contact between said pressure members.

11. In apparatus for securing drawstring bags: a conveyor adapted to move said bags along a predetermined path, said conveyor including means to hold the drawstrings of said bag taut whereby to close the opening thereof; a pair of rolls of adhesive tape, one supported on either side of said path, said rolls having lengths thereof extending therefrom with ends of said lengths in adhesive contact at a juncture point in said path with the adhesive surfaces facing against said conveyor movement whereby said drawstrings of bags moving in said path encounter said adhesive surfaces at said juncture point; opposed pressure members engaged with the backs of said tape lengths of said juncture point to hold the same in said adhesive contact, one of said pressure members being yieldable to permit said drawstring to pass between said pressure members, and resilient to rejoin said tape in adhesive contact behind said drawstring as the same moves in said path; and sealing means responsive to movement of said conveyor to press portions of said tape into mutually adhering contact around said drawstrings of a bag when the latter is just beyond said juncture point in said path.

12. In apparatus for securing drawstring bags: a conveyor adapted to move said bags along a predetermined path, said conveyor including means to hold the drawstrings of said bag taut whereby to close the opening thereof; a pair of rolls of adhesive tape, one supported on either side of said path, said rolls having lengths thereof extending therefrom with ends of said lengths in adhesive contact at a juncture point in said path with the adhesive surfaces facing against said conveyor movement whereby said drawstrings of bags moving in said path encounter said adhesive surfaces at said juncture point; opposed pressure members engaged with the backs of said tape lengths of said juncture point to hold the same in said adhesive contact, one of said pressure members being yieldable to permit said drawstring to pass between said pressure members, and resilient to rejoin said tape in adhesive contact behind said drawstring as the same moves in said path; sealing means responsive to movement of said conveyor to press portions of said tape into mutually adhering contact around said drawstrings of a bag when the latter is just beyond said juncture point in said path; and a cutter connected to said sealing means for concurrent movement therewith, said cutter being disposed to sever said tapes at a point between said drawstrings and said pressure members whereby to leave a portion of said tapes secured in mutually adhering contact around said drawstrings, and ends of said lengths in adhesive contact between said pressure members.

13. In package sealing apparatus of the class described: a conveyor adapted to move packages

10 along a predetermined path; separate supply lengths of adhesive tape, one supported on either side of said path and adhesively joined at a point in said path with the adhesive surfaces of said lengths facing toward the path of said packages, whereby said packages moving in said path encounter said adhesive surfaces at said juncture point; and movable sealing means positioned beside said path adjacent said juncture point, normally out of contact with said tape, and connected to be actuated by movement of said packages to press portions of said tape lengths into securing engagement with a part of said package when the latter passes said juncture point in said path.

14. In package sealing apparatus of the class described: a conveyor adapted to move packages along a predetermined path; a pair of rolls of adhesive tape, one supported on either side of said path, said rolls having lengths thereof extending therefrom and adhesively joined at a point in said path with the adhesive surfaces of said lengths facing toward the path of said packages, whereby said packages moving in said path encounter said adhesive surfaces at said juncture point; sealing means responsive to movement of said packages to press portions of said tape lengths into securing engagement with said package when the latter is at said juncture point in said path; and severing means carried by said sealing means and positioned to sever said engaged portions from said supply lengths when said sealing means is actuated as aforesaid.

15. In package sealing apparatus of the class described: a conveyor adapted to move packages along a predetermined path; a pair of rolls of adhesive tape, one supported on either side of said path, said rolls having lengths thereof extending therefrom and adhesively joined at a point in said path with the adhesive surfaces of said lengths facing toward the path of said packages whereby said packages moving in said path encounter said adhesive surfaces at said juncture point; and sealing means adjacent said juncture point including a pair of pressure members on opposite sides of said path and normally spaced apart, one of said pressure members being movable toward the other and responsive to movement of said packages to clamp said tapes and a part of said package between said pressure members whereby to secure portions of said tape to said package when the latter passes said juncture point in said path.

16. The construction of claim 15 further characterized by having a cutter carried by said movable pressure member adjacent a rearward edge thereof to sever said secured tape portions from said supply lengths when said sealing means is operated as aforesaid.

17. In package sealing apparatus of the class described: a conveyor adapted to move packages along a predetermined path; a pair of rolls of adhesive tape, one supported on either side of said path, said rolls having lengths thereof extending therefrom and adhesively joined at a point in said path with the adhesive surfaces of said lengths facing toward the path of said packages whereby said packages moving in said path encounter said adhesive surfaces at said juncture point; sealing means responsive to movement of said packages to press portions of said tape lengths into securing engagement with said package when the latter is at said juncture point in said path; severing means carried by said sealing

11

means and positioned to sever said engaged portions from said supply lengths when said sealing means is actuated as aforesaid; and yielding pressure means engaged with said tape lengths immediately behind said severing means to rejoin said supply lengths whereby to leave said lengths joined in readiness for another package moving in said path.

18. In apparatus for securing drawstring bags: a conveyor adapted to move said bags along a predetermined path, said conveyor including means to hold the drawstrings of said bag taut whereby to close the opening thereof; a supply of fastening material supported adjacent a predetermined point in said path and disposed to engage said drawstrings adjacent the mouths of said bags; and a movable pressure sealing member positioned adjacent said point and responsive to movement of said bags to press a portion of said material into securing engagement with said drawstrings when the latter pass said point, said sealing member extending rearwardly from said point in said path to secure other portions of said material together behind said drawstrings.

10

12

19. The construction of claim 18 further characterized by having a cutter mounted on said pressure member at the rearward edge thereof to sever said secured material portions from said supply.

CECIL MILLER.
